UNITED STATES PATENT OFFICE.

OAKES AMES, OF MILTON, AND ISAAC W. LITCHFIELD, OF BOSTON, MASSACHUSETTS, ASSIGNEES TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

No. 923,287.

Specification of Letters Patent.

Patented June 1, 1909.

Application filed October 12, 1905. Serial No. 282,410.

To all whom it may concern:

Be it known that we, OAKES AMES and ISAAC W. LITCHFIELD, said AMES of Milton, county of Norfolk, State of Massachusetts, and said LITCHFIELD of Boston, in the county of Suffolk and State of Massachusetts, have invented certain new and useful Improvements in Pneumatic - Despatch - Tube Apparatus, of which the following is a specification.

Our invention relates to improvements in pneumatic despatch tube apparatus and its principal object is to despatch carriers without breaking the air circuit and also to enable the carriers to be automatically introduced into the transmission tube when the vacuum is strong without injury to the carriers.

The advantage of this device is that the air circuit is not even momentarily interrupted by the introduction of a carrier thus preventing the stopping of the carriers in transit previous to their delivery. In practice we have found that carriers have been arrested in their travel through the tube by the air circuit being broken so that they would become lodged in the tube and would not start when the air circuit was restored. This condition is particularly noticeable when the carriers are ascending through a vertical section of the tube circuit.

In the accompanying drawings which illustrate a construction embodying our invention, Figure 1 is a vertical section showing the general arrangement of the device in normal position. Fig. 2 is a side elevation showing the carrier held in check before opening the balance valve until the inlet valve is closed. Fig. 3 is a rear elevation of Fig. 2 with the inlet valve in the position shown in Fig. 1. Fig. 4 is a side elevation with parts broken away showing a carrier passing through balance valve and the inlet valve closed.

Like letters of reference refer to like parts throughout the several views.

A carrier despatcher M of the type shown and described in U. S. Letters Patent #687,201 issued Nov. 26, 1901, to James T. Cowley, is attached directly above the balance valve chamber M² by means of a piece of tube M' of the same diameter as the transmission tube R, forming an inlet normally

sealed from the atmospheric pressure exerted in the transmission tube R by means of the balance valve which consists of the two leaves J and J' connected by the link J² and hung on the pivot J³. A chamber I which is connected with the chamber M² contains the cam or stop G pivoted therein by the pin H. The plunger F permits free movement of the stop or cam except when the plunger descends by gravity when the cradle M releases the bell crank lever A which is pivoted to the support B by the pin C and connected to the plunger F by the pivot D. The upper arm of the bell crank lever A is operated through the movement of the cradle M throwing the plunger F down; then the cradle is moved forward and up when released to normal position through the medium of the spring T. The buffer L is mounted on the cradle M and cushions the contact of the said cradle M and the end of the bell crank lever A at the end of the rearward movement of said cradle. The buffer B' mounted in the support B cushions the drop of the plunger F.

The operation is as follows: The carrier Z is placed in the cradle M as shown in Fig. 1 which cradle is provided with a valve K normally closing the tube inlet. The handle L is then pushed inwardly by the operator until the cradle M swings into alignment with the tube M' when the carrier drops into said tube M' and is arrested and held by the cam or stop G (Fig. 2). The inward motion of the cradle M releases the bell crank lever A allowing the plunger F to drop thereby locking the cam G in position to arrest and hold the carrier Z. The handle L is then released by the operator and the cradle M is returned to normal position by the action of the spring T. Valve K now closes the inlet and the bell crank lever A has been thrown back by the return of the cradle M thereby throwing up the plunger F and releasing the cam or stop G allowing the carrier Z to drop striking the leaf J of the balance valve causing the said valve to open by the weight of the carrier thereon allowing the carrier to pass through as shown in Fig. 4. The balance valve now automatically closes and the operation has been accomplished without momentarily breaking the air circuit in the transmission tube R.

Having thus described the nature of our invention and set forth a construction embodying the same, what we claim as new and desire to secure by Letters Patent of the 5 United States is—

1. In pneumatic despatch tube apparatus, a transit tube communicating with a source of air-pressure, a carrier-inlet opening into said transit tube, independently operated outer and inner valves in said carrier-inlet to close the latter to outside air, and means for arresting the carrier in said carrier-inlet between said valves out of contact with the inner valve while the outer valve is being 15 closed.
2. In pneumatic despatch tube apparatus, a transit tube communicating with a source of air-pressure, a carrier-inlet opening into said transit tube, independently operated outer and inner valves in said carrier-inlet to close the latter to outside air, a movable stop for arresting the carrier in said carrier-inlet between said valves out of contact with the inner valve while the outer valve is being 20 closed, and mechanism actuated by said outer valve to disengage the stop from the carrier on the closing of the outer valve.
3. In pneumatic despatch tube apparatus, a transit tube communicating with a source of 25 air-pressure, a carrier-inlet opening into said transit tube, independently operated outer and inner valves in said carrier-inlet to close the latter to outside air, a movable stop for arresting the carrier in said carrier-inlet between said valves out of contact with the inner valve, and mechanism actuated by the outer valve to move said stop to engage the carrier on the opening of the outer valve and

to move the stop to disengage the carrier on the closing of the outer valve.

4. In pneumatic despatch tube apparatus, a transit tube communicating with a source of air-pressure, a carrier-inlet opening into said transit tube, independently operated outer and inner valves in said carrier-inlet to 40 close the latter to outside air, a pivoted stop, a plunger for moving said stop into the carrier-inlet to engage the carrier to hold the latter between said valves out of contact with the inner valve, and a bell-crank connected 45 with said plunger actuated by the closing of the outer valve to move the plunger to free the stop from the carrier.

5. In pneumatic despatch tube apparatus, a transit tube communicating with a source 55 of air-pressure, a carrier-inlet opening into said transit tube, a manually operated valve for closing the outer end of said carrier-inlet, a balance valve normally closing the inner end of said carrier-inlet when the manually 60 operated valve is open, a movable stop for arresting the carrier in said carrier-inlet between said valves out of contact with the balance valve, and mechanism actuated by said manually operated valve to disengage the 65 stop from the carrier on the closing of said manually operated valve.

In testimony whereof, we have signed our names to this specification in the presence of two subscribing witnesses, this ninth day of October A. D. 1905.

OAKES AMES.
ISAAC W. LITCHFIELD.
